UNITED STATES PATENT OFFICE.

HERBERT E. FOWLER, OF NEW HAVEN, CONNECTICUT, ASSIGNOR OF ONE-HALF TO L. N. BLYDENBURGH, OF SAME PLACE.

POLISHING-WHEEL.

SPECIFICATION forming part of Letters Patent No. 373,653, dated November 22, 1887.

Application filed December 27, 1886. Serial No. 222,533. (No model.)

To all whom it may concern:

Be it known that I, HERBERT E. FOWLER, of New Haven, in the county of New Haven and State of Connecticut, have invented a new 5 Improvement in Polishing-Wheels; and I do hereby declare the following, when taken in connection with accompanying drawings and the letters of reference marked thereon, to be a full, clear, and exact description of the same, 10 and which said drawings constitute part of this specification, and represent, in—

Figure 1, a longitudinal central section through the wheel; Fig. 2, a face end view.

This invention relates to an improvement in 15 that class of polishing-wheels which are composed of flexible material, so as to present a soft or yielding fibrous surface to the article presented thereto.

In the more general construction of this class 20 of wheels numerous circular disks are cut from cloth—usually cotton—and these disks are placed upon a concentric shaft between two collars or heads of smaller diameter than the disks of fibrous material, and are clamped 25 by these collars so as to be held firmly upon the shaft, and so that the wheel thus produced will revolve with the shaft. The fibrous disks project outside the periphery of the collars and present a fibrous periphery for the polishing-wheel. The collars or heads are necessarily 30 large in proportion to the disks of fibrous material in order to properly support the disks.

In the use of this class of polishing-wheels 35 the wear is rapid, and, as the wheel cannot be used to a point inside the periphery of the collars, it follows that there is a very considerable waste of material. Another difficulty in the use of this class of wheels arises from the 40 liability of bringing the work to be polished accidentally into contact with the collars, such contact unavoidably injuring the surface or article being polished.

These wheels are expensive because of the 45 great amount of time required in cutting out the disks and arranging them between the collars.

The object of my invention is to overcome 50 the difficulties experienced in the use of this class of wheels, as well as to produce the wheel

at very much less cost; and my invention consists in a wheel composed of a head concentric with the driving-shaft, having the fibrous material applied thereto substantially parallel with the axis of the head, and so as to 55 project from the head in such parallel direction and present a free polishing-edge in a plane substantially at right angles to the axis of revolution.

In producing my improved polishing-wheel 60 I prefer to employ a long strip of suitable fabric—say, as coarse muslin, canton-flannel, or felt—the width of the strip in accordance with the size or requirements of the wheel.

A represents the head, which is provided 65 with a suitable socket, B, by which it may be secured to the revolving shaft. Onto the periphery of this head one end of the strip is secured, preferably close to one edge of the strip, and so that the strip will project from 70 the face of the head, as seen in Fig. 1. Then the strip is wound around the head in successive convolutions until the required size or body of polishing-surface is attained. The strip is then secured to the head in any suit- 75 able manner, may be by nails, or it may be glued in the process of winding. This completes the wheel. The central portion of the wheel is open, the fibrous material presenting a concentric ring of polishing-surface in a 80 plane at right angles to the axis.

The head is applied to the shaft and caused to rapidly revolve, as in the usual construction of this class of wheels; but instead of presenting the polishing-surface parallel with the 85 axis, as in the usual construction, the free edge of the strip is employed, and in a plane at right angles to the axis. In this construction the labor of cutting out the disks is avoided, and the waste consequent upon such cutting is also 90 avoided. In the case of wheels of this construction, a much greater extent of acting-surface is brought upon the article than can be in a cyl- 95 indrical wheel, for the reason that whereas in a cylindrical wheel the attack of the wheel is at a point only, without any considerable extent of bearing, in my improved wheel the article to be polished, being placed against the wheel in a plane at right angles to the axis, will be covered by a large plane of the acting- 100

surface of the wheel. Again, in the use of my improved wheel the liability of bringing the article into contact with the clamping-collars is avoided. Again, the amount of material required to secure the strip to the head is very much less than that portion of the disks which stand within the collars. Consequently, there is less waste or loss of material applied to the wheel.

10 The open center of the wheel leaves a clear space, so that the work to be polished may be run across the ring-like polishing surface, the central space permitting the dust and fiber to escape, and in the case of a moist polishing material it avoids clogging at the center, as it would do were the center solid fiber or closed.

15 I have mentioned only a fibrous material as cloth, &c.; but it will be understood that the usual materials employed in this class of 20 wheels for polishing purposes may be applied in this wheel.

25 I am aware that it is common to form a polishing-wheel by winding a strip of material upon a cylindrical body; but I am not aware that a polishing-wheel has been made consist-

ing of a head with a strip of fibrous material of greater width than the thickness of the head wound upon and secured to the head so as to leave the several convolutions projecting from the head parallel with the axis free and flexible, which is the essential feature of my invention.

I claim—

The herein-described polishing-wheel, consisting of a concentric head, combined with a strip of flexible fibrous material, of greater width than the thickness of the head, wound upon the head in successive convolutions, the said convolutions secured to the head only, so as to leave the remainder of the strip projecting from the said head in the direction of the axis of the head, the said convolutions in their projection in the head being free and independent of each other and so as to retain their natural flexibility, substantially as described.
